DESIGN FOR A THERMOMETER

George E. Ford, Rochester, N. Y., assignor to
Rochester Manufacturing Company, Rochester, N. Y.

Application November 15, 1939, Serial No. 88,287

Term of patent 7 years

To all whom it may concern:

Be it known that I, George E. Ford, a citizen of the Dominion of Canada and a subject of the King of Great Britain, residing at Rochester, in the county of Monroe and State of New York, have invented a new, original, and ornamental Design for a Thermometer, of which the following is a specification, reference being had to the accompanying drawing, forming a part thereof.

Figure 1 is a front elevation of the thermometer showing my new design.

Figure 2 is a side elevation thereof.

Figure 3 is a rear elevation thereof.

I claim:

The ornamental design for a thermometer, as shown.

GEORGE E. FORD.
